[57] CLAIM

The ornamental design for a fishing rod, or the like, as shown and described.

DESCRIPTION

FIG. 1 is a perspective view of a fishing rod, showing my new design;

FIG. 2 is a top plan view thereof;

FIG. 3 is a bottom plan view thereof;

FIG. 4 is an enlarged rear elevational view thereof; FIG. 5 is an enlarged front elevational view thereof; and

FIG. 6 is a side elevational view, the opposite side being a mirror image thereof.

FIG. 2.

FIG. 4.
